John L. Spalding.

UNITED STATES PATENT OFFICE.

JOHN LUTHER SPALDING, OF AITKIN, MINNESOTA.

BLACKING-BRUSH.

SPECIFICATION forming part of Letters Patent No. 391,491, dated October 23, 1888.

Application filed March 30, 1888. Serial No. 268,982. (No model.)

To all whom it may concern:

Be it known that I, JOHN LUTHER SPALDING, a citizen of the United States, residing at Aitkin, in the county of Aitkin and State 5 of Minnesota, have invented a new and useful Improvement in Blacking-Brushes, of which the following is a specification.

The invention relates to improvements in blacking-brushes, being a device that can be 10 carried in the pocket and at any time taken out and used to rub the shoes over with a blacking and polishing compound and afterward returned to the pocket without soiling the hands or clothes; and it consists in the construction and novel combination of parts hereinafter described, illustrated in the accompanying drawings, and pointed out in the 15 claims hereto appended.

In the drawings, Figure 1 represents a perspective view of the device closed. Fig. 2 represents a central longitudinal section of the device. Fig. 3 represents a perspective view of the protective cap. Fig. 4 represents a perspective view of the sponge-brush 20 detached. Fig. 5 represents a side view of the regulating valve-rod. Fig. 6 represents the central longitudinal section of the cylindrical receptacle that forms the body of the device.

Referring to the drawings by letter, A designates the cylindrical body of the device, formed, preferably, of plate metal and having one end, a , preferably rounded, the said end being the upper end. The end a has a central 25 circular opening, a' , formed by the introversion of the metal, which introversion constitutes the internally-tapped axial sleeve a^2 . The opposite or lower end, a^3 , of the body is reduced in size, being separated from the 30 larger main portion by the circumferential shoulder a^4 , having a height equal to the thickness of the shell. The said end is externally threaded, as at a^5 , to engage the internally-threaded mouth of the rounded protective cap 40 B, that screws thereon and closes the device. When closed, the external surfaces of the body and cap are flush with each other.

At the lower end, a^3 , of the body is the inwardly-standing peripheral flange, b , threaded

on its edge to engage the tapped stem c of the sponge-brush holder C, which holder is tubular and provided at a suitable point, about midway of its length, with the milled-edge collar c' . When said holder is in place, its inner orifice, c^2 , opens into the body or receptacle. The outer end of said holder is flared or flanged outwardly, as at c^3 , for the better attachment of the sponge-brush D, which is secured upon said outer end by wires or otherwise, its base abutting against the collar c' . The said sponge-brush is roughly cone-shaped, and the outer orifice of the holder opens about centrally within it.

When the device is closed, the sponge-brush rests within the rounded protective cup B.

E is the conical regulating-valve, which enters the inner orifice of the holder; and e is the rod of the same running axially through the body and at its tapped portion e' engaging the sleeve a^2 . On its end, outside the body, the 60 said rod is provided with the rounded head e^2 , by means of which it may be turned with the fingers.

When the cap is screwed on the body or receptacle, the latter being full of the blacking 75 and the valve E screwed tightly into the inner orifice of the sponge-brush holder, the device can be carried in the pocket without risk of spilling the contents. When it is desired to use the device, the cap is removed and the 80 conical valve screwed out from the orifice c^2 more or less, according to the amount of blacking desired to flow.

Having described my invention, I claim—

1. The combination of the receptacle having 85 a threaded flange, b , at its lower end, the cap fitted to said end, the brush-holder having a threaded portion engaging said flange, a milled flange, c' , a flanged portion to which the brush is secured, and a valve engaging the brush-holder, as set forth.

2. The herein-described blacking-brush, comprising the body having the internally-threaded introverted axial sleeve at its outer end, the threaded inner end, and the threaded 95 peripheral flange standing inward from its inner end, the protective cap screwing on the inner end of the body, the sponge-brush, the

tubular sponge brush holder screwing into the threaded peripheral flange, and the conical valve resting in the internal orifice of the brush-holder and having a rod provided with 5 a threaded part to engage the introverted axial sleeve, and a head on its end without the body, substantially as specified.

In testimony that I claim the foregoing as my own I have hereto affixed my signature in presence of two witnesses.

JOHN LUTHER SPALDING.
